UNITED STATES PATENT OFFICE.

FRANCIS J. MOORE, OF MINNEAPOLIS, MINNESOTA.

TESTING-PLUG.

1,324,261.

Specification of Letters Patent.

Patented Dec. 9, 1919.

Application filed October 25, 1918. Serial No. 259,698.

To all whom it may concern:

Be it known that I, FRANCIS J. MOORE, a citizen of the United States, residing at Minneapolis, in the county of Hennepin and 5 State of Minnesota, have invented certain new and useful Improvements in Testing-Plugs; and I do hereby declare the following to be a full, clear, and exact description of the invention, such as will enable others 10 skilled in the art to which it appertains to make and use the same.

My present invention has for its object to provide an extremely simple and highly efficient temporary sealing plug for vent 15 pipes and the like. To the above end, the invention consists of the novel devices and combinations of devices hereinafter described and defined in the claim.

In the accompanying drawings, which 20 illustrate the invention, like characters indicate like parts throughout the several views.

Referring to the drawings,

Figure 1 is a fragmentary view, partly in elevation and partly in central vertical section, illustrating the invention applied in 25 a jacket-equipped vent pipe;

Fig. 2 is a view corresponding to Fig. 1, with the exception that the sealing plug has been moved into a position to break the 30 seal;

Fig. 3 is a view of the vent pipe after the sealing plug and seal have been removed; and

Fig. 4 is a view corresponding to Fig. 3, 35 with the exception that the upper end of the jacket has been bent downward into said vent pipe.

Fig. 5 is a fragmentary view of the upper 40 end of the vent pipe illustrating the clamping band in detail.

The numeral 5 indicates a vent pipe having a jacket 6 spaced apart therefrom to afford an air chamber, the upper end of which is closed by a sleeve 7 of relatively soft material, preferably sheet lead. This sleeve 7 is telescoped onto the upper end of the jacket 6 and soldered or otherwise secured thereto to afford a tight joint. The upper end portion of the sleeve 7 is contracted to bring the same into close contact with the upper end portion of the vent pipe 5 and is also extended thereabove, as best shown in Fig. 3, for a purpose that will presently appear.

55 A clamping band 8, the ends of which are connected by draw bolts 9 is applied around

the contracted portion of the sleeve 7 for drawing the same against the vent pipe 5 to form an air, water and gas tight joint between said sleeve and vent pipe. Obviously, 60 the pliable nature of the material from which the sleeve 7 is formed permits the same to be fitted against pipes, which vary slightly in diameter and that are irregular in shape.

To temporarily seal a vent pipe, while the roughed-in plumbing work is being tested for leaks, I provide a sealing plug 10 having an axially projecting stem 11. This sealing plug 10 has an outturned base 70 flange 12, of such material as to loosely fit within the vent pipe 5 and the side walls of said sealing plug are upwardly tapered from said flange. A holder 13 is provided for suspending the sealing plug 10 in the vent 75 pipe 5, either in a raised operative position or a lowered inoperative position. As shown, this holder 13 is of U-shape and the transverse member thereof is loosely mounted in a transverse bore in the stem 80 11. Longitudinally spaced shoulders 13' on the transverse member of the holder 13 engage opposite sides of the stem 11 to keep the holder properly positioned with respect to the sealing plug.

The width of the holder 13 is such as to permit the free ends of its arms, when turned down, to rest upon the top of the vent pipe 5 and support the sealing plug 10 in its uppermost or operative positions, as 90 shown in Fig. 1. In this position of the holder 13, the joint between the vent pipe 5 is closed by first placing oakum 14 and then pouring melted lead 15 thereon, which is afterward calked by the use of a suitable 95 calking tool. The purpose of the oakum 14 is, of course, to prevent the molten lead 15 from running down between the vent pipe and sealing plug.

After the proper tests have been made, 100 the seal in the vent pipe 5 is broken to put the system in operative condition by first turning the holder 13 to lift its arms out of engagement with the sealing pipe. In case the free ends of the arms of the holder 105 should strike the projecting upper end of the sleeve 7, during the swinging movement of the holder 13, said sleeve will yield to permit said arms to pass the same. After the holder 13 is released from the vent pipe 110 5, the plug 10 is forced down out of contact with the seal 15 by pounding on the upper

end of its stem 11. Obviously, the sealing plug 10 will free itself from the lead seal 15 very easily, owing to its tapered engagement therewith.

- 5 The downward movement of the sealing plug 10 is limited by the engagement of the shoulders formed by the inner ends of the arms of the holder 13 with the upper end of the vent pipe 5, as shown in Fig. 2.
- 10 While the sealing plug 10 is thus suspended in the vent pipe 5, the lead seal 15 may be removed from the vent pipe by driving a chisel or other tool between the vent pipe and seal and then bending said seal inward
- 15 to collapse the same. After the lead seal 15 is removed from the vent pipe 5, the sealing plug 10 may be lifted therefrom, together with the oakum 14, with any chips or dirt, which may have dropped thereon.
- 20 With the seal removed from the vent pipe, the upper end of the sleeve 7 may be pounded down over the upper end of the vent pipe 5 and against the inner walls thereof, as shown in Fig. 4. The purpose of thus extending
- 25 the sleeve 7 over the upper end of the vent pipe 5 and downward therein, is to give the work a neat and finished appearance and also to do away with all rough or uneven surfaces in which water and dirt might
- 30 collect.

From the above description, it is evident that by the use of the improved sealing plug, vent or other pipes, either with or without frost-proof jackets, may be efficiently tem-

porarily sealed. It is also evident that the 35 holder 13 not only affords means for suspending the sealing plug in an operative position in a pipe, but it prevents the sealing plug or other parts from dropping into said pipe and thereby clogging the same. 40 As the holder 13, either in its operative or inoperative position, projects above the upper end of the sleeve 7, the same serves as an indicator for an officer or other person to determine whether or not the seal has 45 been removed from the vent pipe.

By the use of the improved sealing plug, the only appreciable expense is the time required in sealing the vent pipe and the removal of the same therefrom, for the reason 50 that the sealing plug will last indefinitely and the lead may be melted and used over and over again.

What I claim is:—

The combination with a vent pipe, of a 55 sealing plug having a stem, and a U-shaped holder having its intermediate portion loosely mounted in said stem, the arms of said holder when turned either upward or downward arranged to engage the upper end of the vent pipe and support the sealing plug in different positions in the vent pipe.

In testimony whereof I affix my signature in presence of two witnesses.

FRANCIS J. MOORE,

Witnesses:

CLARA DEMAREST,
HARRY D. KILGORE.
